UNITED STATES PATENT OFFICE

ANTON A. RUDD, OF SIDNEY, NEBRASKA

DEVICE FOR DISMANTLING FREIGHT CAR TRUCKS

Application filed January 16, 1932. Serial No. 587,128.

This invention relates to devices for facilitating the removal of the sides of freight car truck frames and bolsters, and more particularly to a device of this kind which is so constructed as to eliminate the scratching or injuring of the journals.

An object of this invention is to provide a device of this kind which is so constructed that it can be placed alongside any desired freight car frame or wheel carrying frame for railway cars which will support the bolster and side of the truck frame while the other component parts are released and which is provided with means whereby the frame side may be moved out of the way so that the wheels may be readily changed.

A further object of this invention is to provide a device of this kind having means whereby the frame side may not only be removed without scratching of the journals but may be replaced without scratching of the journals.

A still further object of this invention is to provide a safe handling means for the relatively heavy parts comprising the truck frame of a railway car so that these parts can be handled without injury thereto or to the workmen.

The above and various other objects and advantages of this invention will in part be described and in part be understood from the following detailed description of the present preferred embodiment, the same being illustrated in the accompanying drawings, wherefore in:

Figure 1 is a detail side elevation partly broken away of a device constructed according to the preferred embodiment of this invention;

Figure 2 is a longitudinal section taken substantially through the center thereof;

Figure 3 is a fragmentary front elevation taken on the line 3—3 of Figure 1;

Figure 4 is a fragmentary side elevation partly in section of the frame side supporting brace mounted on the carriage;

Figure 5 is a sectional view taken on the line 5—5 of Figure 3.

Referring to the drawings wherein like numerals designate corresponding parts

throughout the several views, the letter F designates generally a frame structure of substantially U-shaped form and the numeral 10 designates generally an upright frame or support secured to this lower frame F, this support 10 being constructed in two parts one on each side of the frame F with the upper ends of each part disposed in spaced parallel relation to each other. These uprights 10 are preferably constructed in substantially inverted V-shaped form with one leg 11 thereof substantially vertical and another leg 12 extending from the upper end of this vertical leg 11 to the end of the frame F. In this manner, the vertical leg 11 will be disposed intermediate each end of the frame F.

A beam B is mounted on a bar or shaft 13 extending between the upper ends of the opposed frame members 10 and this beam B has a substantially horizontally disposed upper end portion 14 which is extended downwardly from the bar or mounting, as at 15, and the lower end of this extension 15 is secured by means of a bolt or rivet 16 or the like to the rear end of the frame F. This beam B constitutes a portion of a crane and the length of this horizontal extension 14 is such as to extend slightly beyond the forward end of the frame F. A sheave 17 is mounted in the forward end of the beam 14 and a cable or flexible member 18 is trained thereover and has secured to one end a link 19 which is provided with depending loops or hooks 20 at each end thereof, the purpose for which will be hereinafter described.

A drum 21 is mounted on a shaft 22 journaled in the upright frame members 10 and this shaft 22 has secured thereto a worm gear 23 which is engaged by a worm 24 journaled in the side of one frame member 10. A bell crank 25 is secured to a shaft 26 rotatable with the worm 24 so that this worm 24 may be rotated at a point rearwardly of the upright frame member 10. The opposite parallel leg members 27 and 28 of the frame members F are provided at the forward ends thereof with a downwardly opening notch 29 within which the rail 30 is received so as to not only support the forward end of the

frame F but also prevent lateral movement of this frame F with respect to the rail 30.

A transversely extending shaft 31 is journaled in the frame members 27 and 28 intermediate each end thereof and a pair of forwardly extending parallel guide members 32 are secured to this shaft 31 in spaced relation to each other and extend in the direction of the forward end of the frame F. A 10 carriage C which is provided with slide members 33 engaging the guide rods 32 is slidably mounted on the guide rods 32. An operating lever 34, which is rockably mounted as at 35 on the rear frame F and secured to 15 the horizontal connecting bar 36 extending between the slides 33, is secured to the carriage C adjacent the middle thereof by means of a connecting link 37. In this manner, the 20 rocking of the operating lever 34 will move the carriage C on the guide rods 32.

A pair of wedge blocks 38 are removably mounted on the connecting bar 36 and these wedge blocks have the upper surface thereof positioned in downwardly covering relation so as to engage the tapering edges of the frame side S so that when the side is engaged with the carriage C, the bottom of the side will rest on the connecting bar 36 and the tapering sides will be engaged with 25 these wedge blocks 38. The wedge blocks 38 have a slot 39 to receive the connecting bar 36 and the sides of the block 38 are extended upwardly, as at 40, so as to engage on the opposite faces of the frame side upwardly from 30 the bottom thereof and prevent lateral movement of the frame side on the carriage C.

A substantially U-shaped brace or support 41 has one leg thereof secured to the connecting bar 36 and the other leg is relatively 40 short and provided with a laterally extending upper end portion 42 for receiving a truck side supporting block 43. This supporting member 43 cooperates with the wedge blocks 38 in holding the frame side 45 in upright or vertical position on the carriage C so that the carriage may be moved forward or backward on the guide rods 32. A rock shaft 44 extends between the frame members 27 and 28 adjacent the forward end thereof and inwardly of the slots 27 and is 50 provided with cam members 45 for engagement with the guide members 32 so that when this shaft 44 is rocked, the cam portions 45 will raise or lower the guide rods 32 and 55 actively raise or lower the carriage C. An operating lever 46 is secured to one end of this rock shaft 44 and extends alongside one of the frame members. This lever 46 is held in adjusted position by means of a catch or 60 rack member 47.

A shaft 48 extends between the parallel legs 27 and 28 inwardly of each end thereof and preferably adjacent the longitudinal center and a pair of wheels 49 are journaled 55 in wheel mountings 50 carried by this shaft

48. A lever 51 is secured to the shaft 48 and the rocking of this lever 51 will carry the wheels 49 into or out of engagement with the ground so that the frame F can be wheeled or rolled to the desired point. When the 70 wheels 49 are in operative position, the lever 51 is in a position alongside the lower frame member 28 and is held in this position by means of a catch or latch member 52. When the wheels 49 are in inoperative 75 position, the lever 51 is in substantially vertical position.

In the use of this device, the frame F may be wheeled or moved to the side of the car truck by lowering the wheel carrying lever 51 so as to rock the shaft 48 and lower the 80 wheels 49. The notches 29 of the frame members 27 and 28 are engaged with the rail and in this position, the crane beam 14 will substantially overlie the bolster of the wheel truck. The bolster engaging members 20 may then be secured to the bolster inwardly of the frame side S whereupon the drum 21 may be rotated through the worm gear structure 23 and 24 by rotating the bell crank 25, thereby raising the bolster to remove the 85 springs, roller spring seat and rollers. The bolster may then be lowered so that the end thereof will be positioned in the wide opening of the side frame. The carriage C may then be raised in its forward position to 90 engage and raise the side frame S whereupon the journal bearing wedges and journal bearings are removed. The wedge blocks 38 may be secured in position on each side of the carriage C and the frame side supporting member 43 put into position so as to prevent 95 tilting of the frame side on the carriage C as it is moved rearwardly by rocking the lever 34 rearwardly of the frame F. The movement of the carriage C inwardly of the frame F will remove the frame side from the truck and thereby permit the replacing of the 100 wheels and other parts pertaining thereto, which operation is performed without 105 scratching the journals or bearings for the wheel axes. In the adjustment of the carriage C beneath the frame side, the cam shaft 44 may be raised or lowered to the desired 110 point so that the guide bars 32 and the carriage will be in the desired position beneath the frame side. When the wheels and other 115 parts have been replaced, the frame side may then be moved forwardly by rocking the lever 34 which will move the carriage C toward 120 the wheel truck and in this operation, the cam shaft 34 may be suitably adjusted so that there will be no scratching of the journals or bearings during the reassembling of the truck. 125

It will be noted from the foregoing that the heavy side of the truck frame and the bolster may be easily and readily handled without scratching or injuring of the bearings or journals and that the frame side may 130

be easily moved away from the wheels so as to permit the replacement of worn out wheels or other parts relating to the wheel structure. In practice, there will preferably be two of these devices in use at one time, one on each side of the truck.

It is, of course, understood that various changes and modifications may be made in the details of construction and design of the above specifically described embodiment of this invention without departing from the spirit thereof, such changes and modifications being restricted only by the scope of the following claims.

15 What is claimed is:—

1. A device as described comprising a frame, a carriage, guide members carried by the frame, means for swingably mounting the guide members in the frame, and guide 20 adjusting means mounted in the frame and engaging the guides for adjusting the guides relative to the frame to raise or lower the carriage, said means including an eccentric, an operating lever and a toothed rack for 25 holding the lever in adjusted position.

2. A device as described comprising a frame, guide means mounted in the frame, means engaging one end of said guide means for rockably mounting the guide means in 30 the frame, a carriage mounted on said guide means, cam means carried by the frame and engaging the opposite end of said guide means for vertically adjusting said end of 35 said guide means relative to the frame to raise or lower the carriage, a cam operating lever, and means for holding the lever in adjusted position.

3. A device as described comprising a frame, guide means, means for rockably 40 mounting said guide means for vertical swinging movement in the frame, cam means engaging the guide means for vertically adjusting one portion of said guide means relative to the frame, an operating member for 45 said cam means, means for holding the operating member in adjusted position, and a carriage slidably mounted on said guide means.

4. A device as described comprising a frame, a pair of parallel guide members 50 mounted in the frame, means carried by the frame and engaging one end of the guide members to rockably mount said guide members in the frame, cam means engaging the opposite end of the guide means to vertically 55 adjust said opposite end relative to the frame, a cam lever, means for holding the lever in adjusted position, and a carriage slidably mounted on the guide means.

5. A device as described comprising a 60 frame, said frame having a notched forward end portion to engage a transversely disposed rail to prevent lateral movement of the frame relative to the rail, guide means mounted in the frame, adjustable means for adjusting 65 said guide means relative to the frame, a

lever for said adjustable means, means for holding the lever in adjusted position, a carriage slidably mounted on the guide means, operating means for said carriage, and article supporting means carried by the carriage to support an article thereupon in vertical position.

6. A device as described comprising a frame, means for securing the frame to a transversely disposed rail to prevent lateral 75 movement of the frame relative to the rail, guide means mounted in the frame, means engaging one end of said guide means to rockably mount the guide means in the frame, cam means engaging the opposite end of said 80 guide means to adjust said opposite end relative to the frame, an operating lever for said cam means, a latch mounted on the frame and engaging the lever to hold said lever in adjusted position, and a carriage slidably 85 mounted on the guide means.

7. A device as described comprising a frame, means for removably securing the frame to a rail in laterally extended relation to the rail, guide means, means for rockably 90 mounting said guide means in the frame, cam means carried by the frame and engaging said guide means to vertically adjust one portion of said guide means, operating means for said cam means, releasable locking means 95 for holding said cam means in adjusted position, and a carriage slidably mounted on said guide means.

8. A device as described comprising a frame, means for removably securing the 100 frame to a transversely disposed rail to prevent lateral movement of the frame relative to the rail, a pair of parallel guide members, means engaging one end of the guide members and extending transversely thereof to 105 rockably mount said guide members in the frame, a cam member mounted in the frame and engaging the opposite end of the guide members to vertically adjust said end of 110 said guide members, operating means for said cam member, releasable holding means for said operating means, a carriage slidably mounted on the guide members, operating means for said carriage, and lifting means carried by the frame and disposed above the 115 carriage to release an article for movement on the carriage longitudinally of the frame.

In testimony whereof I hereunto affix my signature.
